LOW TEMPERATURE DISTILLING APPARATUS AND METHOD OF USING THE SAME

Application filed January 28, 1927. Serial No. 164,166.

My invention relates to low-temperature distilling apparatus that is adapted for distilling carbonaceous material such as lignite, shale, peat or bituminous coal. My invention relates specifically to such apparatus as embodies heating walls that are suspended from one side thereof.

My invention has for one of its objects to provide apparatus for low-temperature distillation of carbonaceous materials in which the heating walls therefor are so constructed and arranged that they are self-aligning, regardless of temperature variations to which they may be subjected.

A second object of my invention is to provide apparatus of the character described above in which the heating walls are provided with means for retaining and supporting material to be treated and which are constructed and arranged to remain in vertical alignment in order to facilitate the removal of the treated material.

A further object of my invention is to provide apparatus that may be easily and conveniently charged with material to be treated and from which the treated material may be readily discharged.

It has been proposed heretofore to provide heating walls that are suspended from one side or edge thereof. Inasmuch as such heating walls have been constructed of cast iron or other similar material that may be subjected to strains by reason of the varying temperature conditions, there is a tendency for the material to become warped and thereby render the operation of removing the treated material more difficult by reason of the misalignment of the spaces for containing the treated material and the pushers or other mechanism for removing the material.

In case the heating walls are composed of a number of sections or bars of material, it has been difficult to secure alignment of the several parts when they were assembled by reason of the fact that their engaging sur-

faces are not parallel and, if the angles are cumulative, the walls are curved. In addition, the wall is not sufficiently flexible between the various sections to permit the wall to straighten when it is heated.

In accordance with the present invention, I provide apparatus for the low-temperature distillation of carbonaceous materials in which walls are heated prior to the introduction of the material to be treated, the walls preferably being provided with means for retaining and supporting a suitable amount of material to be treated by the corresponding walls. The material is placed in position by filling the spaces between the vertical heating walls and then permitting the escape of any excess material.

The heating walls are so constructed that they are automatically self-aligning. The cross-sectional areas of various portions of the walls which are suspended from one side thereof diminish with the distance from the suspended side at such rate that the weight of the wall supported by any reduced portion is sufficient when the wall is heated to insure that the reduced portion is bent, if necessary, to properly align the various portions of the wall.

My invention has been shown and described in connection with apparatus that is similar in certain respects to that constituting the subject matter of my copending application Serial No. 535,791, filed Feb. 11, 1922.

Reference may now be had to the accompanying drawings, in which

Figure 1 is a vertical sectional view of apparatus adapted for low-temperature distillation embodying my invention;

Fig. 2 is a similar view, taken on the line II-II of Fig. 1;

Fig. 3 is an enlarged transverse sectional view of a heating wall and its corresponding supporting bar of the apparatus of Fig. 1;

Fig. 4 is a vertical sectional view of a modified form of heating wall;

Fig. 5 is a similar view of a further modification;

Figs. 6 and 7 are side and end views, respectively, of a further modified form of 5 heating wall;

Figs. 8 and 9 are similar views of a further modification;

Fig. 10 is a side elevational view of a portion of a sectional heating wall;

10 Figs. 11 and 12 are end views of the structure of Fig. 10;

Figs. 13 and 14 are side elevational and vertical sectional views, respectively, of a portion of a sectional heating wall having 15 modified means for connecting the several sections; and

Figs. 15 and 16 are similar views of a further modification.

Referring particularly to Figs. 1 and 2, 20 a distilling chamber 1 is provided with walls 2 of any suitable refractory or heat-insulating material. Within the distilling chamber 1 are a plurality of vertical heating walls 3 that are suspended from water-cooled horizontal bars 4. The distilling chamber 1 is provided with an upper door or cover 5 comprising an outer shell 6 of iron or other suitable material that is filled with any suitable heat-insulating material 25 30 7. The bottom of the distilling chamber 1 is provided with two doors 8 that are each mounted on a horizontal axis, at 9.

The distilling chamber 1 is adapted to be heated by means of fuel, such, for example, 35 as fuel gas, that may be supplied through a pipe 11, air being supplied through a pipe 12. Gas and air flow into a mixing chamber 13 and are burned below the walls 3, suitable outlets for the waste gases being 40 provided by ducts 14 that communicate with the upper portion of the distilling chamber 1. Suitable dampers 15 are provided to regulate the openings in the ducts 14. The distilling chamber 1 is provided at the top 45 with a suitable discharge outlet 16 for the gases of distillation that is controlled by a valve 17.

Reference may now be had to Fig. 3, which 50 illustrates, in enlarged detail, one of the heating walls 3. The wall 3, which may be of iron in any of its forms or similar suitable material of comparatively high heat capacity and high heat conductivity, is formed with a number of horizontally-extending projecting portions 18 on each side thereof. 55 These projections 18 are curved upwardly to any desired degree in order that they may retain material that may be deposited in the recesses constituted thereby. The projections 18 are preferably arranged in pairs on opposite sides of the central body portion 19. The upper end of the wall 3 is provided with an enlarged portion 20 through which extend holes 21 by means of which 60 it may be secured to the corresponding bar 4.

The cross-sectional areas of the main body portion 19 between the projections 18 decrease downwardly substantially in accordance with the decrease in weight to be supported thereby. The lower enlarged portion of the wall 3 is of comparatively large cross-section in order that it may constitute a weight that is useful in assisting in maintaining the vertical alignment of the entire wall.

In the operation of the distilling apparatus of which the heating walls 3 are a part, the latter are heated to temperatures of substantially 1400° F., at which temperatures the material of the walls 3 is somewhat pliable. Accordingly, if the cross-sectional areas are sufficiently reduced at intervals, the weight of the wall and the material to be treated thereby are sufficient to insure the alignment of the wall, regardless of the strains that may be set up therein by reason of the variations in temperature between the maximum of 1400° and the minimum that obtains when the distilling operation has been completed. It will be readily understood that, unless the foregoing or equivalent means were provided, the walls would become warped or curved and their usefulness would be correspondingly diminished.

In the operation of the apparatus of Figs. 1 and 2, the doors 8 are permitted to swing to their open positions, indicated by dot-and-dash lines—Fig. 1. Gas and air are admitted through the pipes 11 and 12, respectively, into the mixing chamber 13. Combustion occurs in the open space below the distilling chamber 1 and the gases of combustion pass upwardly between and around the heating walls 3 and thence out through the discharge outlets to the atmosphere or the stack, as may be arranged. Heat is stored in the walls 3. When the walls 3 have reached approximately their required maximum temperature, the supply of air and gas is cut off and the doors 8 are closed.

The cover 5 is then lifted, for example, by a truck 23, only a portion of the truck being shown, that is provided with levers 24 that are connected to the door 5 and which are operated by means of a hand-screw 25. The truck is then operated to remove the cover 5 horizontally from its position over the distilling chamber 1 and a larry car 26 is placed in position to discharge bituminous coal, or other material that is to be treated in the chamber 1.

In the preferred method of operating the apparatus, sufficient coal is emptied into the distilling chamber 1 to substantially completely fill the space therein to the upper level of the heating walls 3. This arrangement insures that all of the recesses constituted by the spaces between the projections 18 of the heating walls 3 are filled with material. The cover 5 is then replaced in position to

cover the distilling chamber 1. The doors 8 are then opened and all material in excess of that retained by the recesses of the heating walls is allowed to fall into the 5 hopper below the distilling chamber 1, from which it may be removed and returned by any suitable means to the coal-handling apparatus.

The doors 8 are again closed and the distilling 10 operation proceeds. The gases of distillation pass upwardly and out through the discharge pipe 16 to any suitable or desired apparatus for treating or collecting the distillate.

15 When the distilling operation is completed the doors 8 are opened and the carbonized material is removed from the recesses in the heating walls 3 by means of a pusher mechanism shown in Fig. 2. This mechanism comprises a header or plate 30, from which project pusher rods 31 that register and correspond in number with the recesses of the heating walls 3. Each of the rods occupies an opening 32 in one of the walls 2. The header 20 30, together with the pusher rods 31, is actuated by means of a rack-and-pinion mechanism 33 that may be connected to any suitable power device (not shown).

By reason of the fact that heat is rapidly 30 conducted to the coal, a layer of coke is formed adjacent to the surface of the heating wall and, accordingly, the carbonized material is readily removed from the heating walls. The coke is actuated to the farther 35 end of the heating walls into a space at the end thereof, whereupon it falls into the hopper below the distilling chamber 1. The material may be withdrawn from the hopper for shipment or storage, as desired.

40 When the finished charge is completely removed, gas and air are again admitted, as in the manner previously described, and heat is again stored in the heating walls for the succeeding operation.

45 Reference may now be had to Fig. 4, in which a modified form of heating wall is shown. In this heating wall 35, the reduced cross-sectional areas are produced by cores in molding the wall in case the latter is of 50 cast iron, or horizontal slits 36 may be produced by a saw or other means.

In the heating wall 38 of Fig. 5, flexibility of the structure is secured by superposing sections 39, one of the adjacent surfaces of 55 which is provided with a central projecting portion or lug 40, whereby the adjacent plane surfaces are not in engagement. The assembled sections are retained in position by means of vertically extending bolts 41. The 60 bolts 41 are of sufficient cross-sectional area to support the structure, but, when heated, are sufficiently flexible to permit the weight of the structure to aline the several sections.

The heating wall 43 of Figs. 6 and 7 is 65 provided with plane surfaces and flexibility

is secured by horizontal slits 44, the depth of which increases with the distance from the side from which it is suspended. This arrangement is similar in principle to that of the heating wall of Fig. 4.

The heating wall 46 of Figs. 8 and 9 is rendered flexible by means of openings 47 therethrough that are of increasing length progressively downward in the wall.

The heating wall 49 illustrated in Figs. 10, 75 11 and 12 comprises sections 50 that are suspended the one from the other by means of interlocking members 51 of T-shape which occupy recesses 53 of corresponding shape in the associated sections. Relative lateral movement of the several sections may be prevented in several ways. For example, as shown in Fig. 11, a pin 54 may be inserted in corresponding semi-circular recesses 55 of adjacent edges of the sections. As shown in Figs. 10 and 12, a pin 56 may be inserted in aligned inclined holes 57 extending across adjacent edges of adjoining sections, or, as an alternative, adjacent edges may be prevented from lateral movement by means of rivets 58, such as are shown in the upper right-hand corner of Fig. 10.

In the heating wall 59, shown in Figs. 13 and 14, adjacent sections 60 are secured together by means of a bar 61 of I-shape, which occupies slits 62 of substantially T-shape in adjacent edges of the sections.

In the construction shown in Figs. 15 and 16, the heating wall 64 is composed of superposed hollow sections 65 that are substantially rectangular in cross-section. The adjacent sections are secured by bolts 66, suitable holes 67 being provided whereby socket wrenches may be used.

I have provided apparatus that is suitable for the rapid distillation of carbonaceous material at low temperatures that may be constructed of inexpensive materials that are available in large quantities. The apparatus for serving distillation apparatus of 105 the character of my invention may be simple 110 in character and few in number.

It is preferable that the material to be treated be pulverized and dry and, if desired, it may be preheated, in which case the distilling operation is materially shortened, as it is unnecessary to bring the coal to a temperature corresponding with that of the preheated material before the process of distillation begins.

The heating walls are so constructed that they are self-aligning by reason of their weight. Accordingly, the recesses of the heating walls are always in alignment with the pusher rods of the pusher mechanism and the efficiency of the apparatus is not impaired by warping of the heating walls. The latter condition would obtain if the heating walls were of such width and cross-sections as to be inflexible.

The foregoing and other advantages will be apparent to those skilled in the art to which my invention appertains. While I have shown and described certain preferred 5 embodiments of my invention, it is probable that other modifications may be proposed and it is desired, accordingly, that my invention be limited only in accordance with the scope of the appended claims.

10 I claim as my invention:

1. In distilling apparatus, a heating wall that is suspended from one edge thereof, said heating wall being of such reduced horizontal cross-sectional area proceeding progressively from said edge and of metal that is flexible when heated whereby it retains its vertical alinement when subjected to varying temperatures.

2. In distilling apparatus, a metal heating 20 wall that is adapted to be subjected to varying temperatures, said heating wall having portions of progressively reduced horizontal cross-sectional area proceeding from one edge thereof whereby, when said wall is suspended from said edge, its weight tends to retain its vertical alinement.

3. In distilling apparatus, a metal heating 30 wall that is suspended from one of its edges, the horizontal cross-sectional area of certain of its portions varying substantially in accordance with the weight of the portion of the wall supported thereby.

4. In distilling apparatus, a metal heating 35 wall suspended from one edge thereof, said heating wall having portions of reduced cross-sectional areas, which areas vary substantially inversely with the distance from said one edge.

5. In distilling apparatus, a substantially 40 rectangular heating wall suspended from one edge thereof and having horizontally-extending recesses for the reception and retention of material in stationary position to be treated.

45 6. In distilling apparatus, a heating wall suspended from one edge thereof and having horizontally-extending recesses for the reception of material to be treated and having also interspersed with said recesses 50 spaced horizontally extending portions the cross-sectional areas of which diminish with the distance from said one edge.

7. The method of operating distilling apparatus having horizontally spaced members 55 disposed side-by-side having recesses for supporting the material to be treated which comprises filling the spaces between said members with said material to insure a supply thereof for the supporting members and then 60 relieving said spaces of any excess or unsupported material.

8. The method of operating distilling apparatus having horizontally spaced vertical members disposed side-by-side and provided 65 with means for supporting material to be

treated which comprises filling the spaces between said members with said material to insure a supply thereof for said retaining means and then permitting any excess or unsupported material to fall from said spaces. 70

9. The method of operating distilling apparatus having an enclosure containing a horizontal series of spaced vertical members provided with means for retaining material to be treated which comprises substantially filling said enclosure with said material to insure the supplying of material for said retaining means and then emptying said enclosure of any excess or unsupported material. 75

10. The method of operating distilling apparatus having an enclosure containing a horizontal series of spaced vertical members provided with means for retaining material to be treated which comprises closing the bottom of said enclosure, substantially filling said enclosure to insure supplying material to said retaining means, opening the bottom of said enclosure to permit any excess or unsupported material to flow from said enclosure, closing the bottom of said enclosure and then treating the retained material. 80

11. Distilling apparatus comprising a horizontal series of spaced vertically extending members for supporting material thereon to be treated and means for supporting additional material between said members and operable to relieve the spaces between said members of any additional material therein. 95

12. Distilling apparatus comprising horizontally spaced vertical members on substantially the same level provided with means for supporting material thereon to be treated and means adapted to support additional material in the spaces between said members and to permit said additional material to fall from said spaces. 105

13. In distilling apparatus, a heating wall comprising a plurality of vertically alined sections of metal, each of said sections, except the uppermost section, being suspended from the one immediately above it, and connecting means for said sections comprising material of such small cross-section relative to the weight supported thereby that warping strains in one of said sections do not disturb the alinement of adjacent sections. 110

14. Distilling apparatus comprising a vertical wall having a plurality of substantially horizontally extending members that are adapted to support and retain thereon coal to be distilled and are adapted to be heated to such temperature, and to store sufficient heat therein, as to carbonize coal in contact therewith, means for heating said members, and means for removing carbonized coal from said members. 120

15. Distilling apparatus comprising a vertical wall suspended from one of its edges 130

and having a plurality of substantially horizontal ledges extending outwardly therefrom, said ledges being adapted to be heated to such temperature, and to store sufficient heat therein, as to carbonize coal in contact therewith without the application of additional heat during the carbonizing operation, means for heating said ledges, and means for removing carbonized residue from said

10 ledges.

16. Distilling apparatus comprising a wall having a plurality of superposed substantially horizontal shelf-like members extending outwardly therefrom, said wall and said 15 members being of material adapted to be heated and to store sufficient heat to coke coal placed on said members without the supplying of additional heat during the coking operation, and heating means for said wall and

20 said members.

17. Distilling apparatus comprising a heat-storage device having a plurality of substantially horizontal members adapted to retain material thereon to be heated thereby, said 25 device being of such heat-storage capacity as to carbonize coal on said members.

18. Distilling apparatus comprising a heat-storage device consisting of a vertical main body portion and a plurality of substantially 30 horizontal members extending outwardly on both sides of said main body portion and adapted to retain material thereon for treatment by said device, the heat-storage capacity of said device being such that coal on 35 said members is carbonized without the application of additional heat.

In testimony whereof, I have hereunto subscribed my name this 20th day of January, 1927.

FRANZ PUENING.
